UNITED STATES PATENT OFFICE.

JACOB SCHMID, OF NEW BRUNSWICK, NEW JERSEY.

MUSIC-BOX ATTACHMENT FOR CLOCKS.

SPECIFICATION forming part of Letters Patent No. 293,693, dated February 5, 1884

Application filed November 28, 1883. (No model.)

To all whom it may concern:

Be it known that I, JACOB SCHMID, of New Brunswick, in the county of Middlesex and State of New Jersey, have invented certain new and useful Improvements in Music-Box Attachments to Clocks, of which the following is a specification.

This invention has reference to an improved music-box attachment to clocks, so that whenever the clock has struck the full hours the music-box plays a piece; and the invention consists of a music-box arranged on a sounding-board of the clock-case, which is provided with screened escape-openings at both sides. The music-box is connected by an intermediate lever mechanism with a hammer that is lifted by suitable means on the arbor of the hour-hand and dropped by a trip-lever of the striking mechanism as soon as the full hour has struck, so that the intermediate lever mechanism is struck by the hammer and releases a locking-pawl of the cylinder-barrel of the music-box and admits the starting of the same. A small guard-plate at the end of a spring covers the perforation on the end disk of the cylinder-barrel as soon as the pawl is withdrawn by the intermediate lever mechanism and secures the proper starting of the cylinder-barrel until the piece is played, upon which the pawl returns into its normal position.

In the accompanying drawings, Figure 1 represents a front elevation of a clock with my improved music-box attachment, partly in section. Fig. 2 is a vertical transverse section of the same on line *x x*, Fig. 1. Figs. 3 and 4 are respectively a detail front view and a vertical transverse section on line *y y*, Fig. 3, of the music-box and its connection with the mechanism for starting the same. Fig. 5 is a rear elevation of the clock-movement, showing the hammer for starting the music-box. Fig. 6 is a horizontal section of the clock-case on line *y y*, Fig. 1; and Fig. 7 a detail vertical transverse section on line *k k*, Fig. 5.

Similar letters of reference indicate corresponding parts.

A in the drawings represents a clock-movement of any approved construction, and *B* a clock-case inclosing the same.

In the lower part of the clock-case is ar-

ranged a music-box, *C*, which is attached to a sounding-board, *D*, that is screwed to the rear wall of the clock-case *B*. The side walls of the case are provided with screened openings *b b* for the escape of the sounds. A locking-pawl, *a*, which is generally used in music-boxes, takes by a pin at its end into a hole, *a'*, of a disk, *A'*, on the shaft of the cylinder-barrel of the music-box, and permits the starting *60* of the same by the actuating-spring whenever it is withdrawn from the hole *a'*. The main-spring of the music-box is wound up from time to time by a cord, *C'*, which passes through an opening of the side wall of the clock-case to *65* the outside. A thin steel guard-plate, *a''*, is attached to the forward end of a spring, *a''*, that is secured by its rear end to the base-plate of the music-box. The guard-plate *a''* is arranged sidewise of the disk *A'*, and inter- *7c* posed between the pin of the pawl *a* and the hole *a'* at the moment when the pawl *a* is withdrawn from the hole *a'* of the disk, so as to prevent thereby the re-entering of the pin of the pawl by the action of its spring into the *75* hole *a'*, so as to secure the reliable starting of the cylinder-barrel whenever the pawl is re-*80* leased from the disk *A'*. The opposite end of the pawl *a* is connected by a wire, *d*, with one arm of a bell-crank, *d'*, which latter forms by *85* a rest-plate, *d''*, at its other arm, contact with a trip-rod, *e*, that is vertically guided in eyes *e'* of the clock-case. The rod *e* receives a downward pressure by a spiral spring, *e''*, that is interposed between the eye *e'* and collar *e'''* on *85* the trip-rod *e*.

The trip-rod *e* is extended upward to the rear part of the clock-movement *A* and placed in the path of a hammer, *E*, the rod *E'* of which is pivoted to the rear frame of the clock- *90* movement and lifted by a disk, *E''*, that is keyed to the rear end of the arbor *F* of the hour-hand, said disk engaging by a pin, *f'*, of a pivoted and spring-actuated trip, *f*, a wire fork, *f''*, of the hammer-rod *E'*, so that by the *95* turning of the arbor of the hour-hand the hammer *E* is gradually raised, as shown in Fig. 5. As soon as the full hour has been struck by the striking mechanism a trip-arm, *g*, on the pawl of the notched wheel of the striking mech- *100*anism strikes by the hopping of said pawl against the pivoted trip *f*, so that its pin *f'* is

released from the fork f^2 of the hammer-rod, and the hammer dropped with considerable force on the trip-rod e , as shown in dotted lines in Fig. 5. The blow of the hammer is transmitted by the trip-rod e against the tension of its spring e^2 to the bell-crank d' , which, by the wire connection d , withdraws the pawl a from the opening a' of the disk of the cylinder-barrel, which is instantly covered by the guard-plate a^2 , so that the cylinder-barrel is started by the mainspring of the music-box, and thereby a tune played, after the striking mechanism of the clock-movement has finished the striking of the full hour. The disk E^2 continues to rotate with the arbor of the hour-hand until in the course of the next hour it raises the hammer again to its full height, from which it is dropped again by the release of the trip f , owing to the engagement with the trip-arm g , and so on every hour.

When a piece of music has been played by the box and the hole a' of the disk A' comes around again to the pin of the pawl a , the latter quickly re-engages the hole a' and brings thereby the cylinder-barrel to a stop. In this manner a very neat and attractive music-box attachment for clocks is obtained, which is very reliable in its action, and which is heard to advantage all over the room, owing to the arrangement of the sounding-board back of the music-box and the escape-openings for the sounds in the case of the clock.

Having thus described my invention, I claim as new, and desire to secure by Letters Patent—

1. The combination of a clock-movement having a trip-arm on the pawl of the striking mechanism, a trip mechanism on the arbor of the hour-hand, a trip-hammer that is raised by the same and dropped after the full hour is struck, a music-box arranged below the clock-movement, and an intermediate mechanism that extends from a point in the path of the hammer to the locking device of the music-box, so that whenever the clock has struck the full hour the locking device is released

and the music-box set in motion, substantially as set forth.

2. The combination, with a clock-case having screened side openings, of a music-box placed on a sounding-board attached to the case, means connecting the starting device of the music-box with the clock-movement, a trip-hammer pivoted to the rear frame of the movement, a trip device on the arbor of the hour-hand, and a trip-arm of the pawl of the striking mechanism, whereby the music-box is started after each full hour has struck, substantially as specified.

3. The combination of a music-box provided with a locking-pawl and a spring-actuated guard-plate sidewise of the disk of the cylinder-barrel, an intermediate mechanism connecting the pawl with the clock-movement, a trip-hammer pivoted to the frame of the clock-movement and adapted to actuate the intermediate mechanism, a trip mechanism secured to the arbor of the hour-hand and adapted to engage the hammer-rod, and the trip-arm on the pawl of the striking mechanism, that releases the trip mechanism of the arbor from the hammer-rod as soon as a full hour has struck, substantially as set forth.

4. The combination of a music-box, A, having a locking-pawl, a , and a spring-acted guard-plate, a^2 , sidewise of the disk A' of the cylinder-barrel, a connecting-rod, d , bell-crank d' , a vertically-guided and spring-cushioned trip-rod e , a trip-hammer, E , pivoted to the frame of the clock-movement and having a fork, f^2 , a disk, E^2 , on the arbor of the hour-hand, said disk having a spring-acted trip, f , and pin f' , and a trip-arm, g , on the pawl of the striking mechanism of the clock, substantially as described.

In testimony that I claim the foregoing as my invention I have signed my name in presence of two subscribing witnesses.

JACOB SCHMID.
